MEANS FOR AUTOMATIC DEFROSTING OF
REFRIGERATING SYSTEMSCharles W. Bell, Westfield, N. J.; Edythe H. Bell
executrix of said Charles W. Bell, deceased

Application April 30, 1932, Serial No. 608,531

15 Claims. (Cl. 62—4)

This invention relates to the defrosting of cooling elements of refrigerating units or systems and more particularly to means for starting such defrosting automatically when the ice on the cooling element reaches a predetermined thickness and for stopping the defrosting when the ice is melted away to a predetermined thinness.

In domestic and commercial refrigerating units or systems wherein the temperature in a confined space, such as the interior of an enclosed compartment, box or case, is maintained at a definite point or within narrow limits adjacent thereto, there gradually accumulates on such cooling unit a coating of ice or frost which, if it builds up to an excessive thickness, interferes with or prevents satisfactory and proper action of the cooling unit in maintaining efficiently the desired predetermined temperature.

Particularly in domestic refrigerating systems, the primary source of refrigerating effect, or the refrigerant-supplying means, is intermittently operated in accordance with the action of a suitable control caused to operate, for example, by variations of pressure within the system or variations of the temperature in the compartment or the space within which cooling is to be effected or of the cooling unit itself. Heretofore, irrespective of the particular nature of the control, defrosting has been effected by manually stopping the operation of the refrigerant-supplying means and leaving it in this condition until the ice coating has melted either completely or to a desired degree of thinness. The usual instructions are to effect the defrosting operation at regular fixed intervals but these intervals may well be varied for the convenience of the operator and in view of the varying rates of growth of the ice coating under various conditions.

An important object of the invention is to provide for automatic control of the defrosting operation in accordance with changes of condition in the refrigerating system which may be considered to include the cooling chamber as well as the closed system in which the refrigerant circulates.

Another object of the invention is to provide, in connection with a refrigerating system automatically started and stopped in accordance with refrigerating conditions, for automatic starting of a defrosting action when the ice on the cooling element reaches a predetermined maximum thickness and automatic stopping of this operation when the ice reaches a predetermined degree of thinness.

Another object of the invention relates to the

provision of means, adapted for use in connection with a system which automatically works intermittently in accordance with the requirements of the system, for testing the thickness of the ice on the cooling element just before the system starts up after each rest period and preventing such starting if the ice is found to have reached a predetermined maximum thickness.

Another object of the invention relates to provision, in connection with a system which automatically works intermittently in accordance with the requirements thereof, not only for testing the thickness of the ice on the cooling element just before the system prepares to start up after each rest period and preventing such starting if the ice be found to have reached a predetermined maximum thickness, but also for permitting such starting when the ice has melted to a predetermined degree of thinness.

Another object relates to the use of a feeler movable toward and from the cooling element of an intermittently operated system, a control device for prevention or permitting the starting of the system, and operating means for normally actuating the feeler without operation of the control device and for actuating the control device when the feeler is stopped by ice of a predetermined maximum thickness on the cooling element, said operating means being restored to normal operation upon completion of the defrosting action.

Further objects of the invention are to provide defrosting means of which a substantial part is self-contained, and may readily be applied to any one of the different types of intermittently operated machines, and to provide defrosting means which will be substantially free from interference, such as by ice on the cooling element.

Preferably the defrosting control includes a feeler movable toward and from a cooling element on which the ice collects, an operating or motor element moving in accordance with changes of conditions in the system, a device, such as a switch or valve, for preventing or permitting operation of the refrigerant-supply means, a device operable by the motor element of the control to reciprocate the feeler or to operate the switch device or valve device to prevent operation of the refrigerant-supply means, and yielding means normally preventing opening of the switch device or closing of the valve device (whichever be used) but yielding when the feeler is checked in its forward movement by engagement with a predetermined thickness of ice on the cooling unit and returning to normal position.

sition when the ice is melted to a predetermined thinness and permits the feeler to advance to a corresponding position. Preferably the device interposed between the motor element of the control and the feeler and the shutoff device is adapted to operate either the feeler or the shutoff depending upon which offers the greater resistance. During ordinary operation the shutoff device is yieldably held against operation thus causing normal operating movement of the feeler which advances during rest or idle periods to a position corresponding with the starting condition of the main control and retracts during active periods of the refrigerant-supplying means. When, however, the movement of the feeler is prevented by engagement of the same with ice of a predetermined maximum thickness on the cooler the shutoff device is operated against such yielding resistance and the defrosting operation is started. Then, as the temperature rises and other changes in condition occur, the condition of the shutoff device is changed further so as to delay the throwing out of the shutoff device. When the ice has been melted to a predetermined thinness and the feeler is advanced accordingly farther than in its normal operating movement, the shutoff device is thrown out of action.

Other objects and advantages will be apparent upon consideration of the following description 30 and of the drawings, in which:

Fig. 1 is a diagrammatic view illustrating one embodiment of the invention as applied to a refrigerating system of the compression-expansion type in which intermittent action of the compressor and the action of the defrosting device are controlled by variations of pressure in the refrigerating system, the parts being shown in the positions assumed just after starting the refrigerating system for the first time or at the end 40 of a defrosting operation;

Fig. 2 is a view similar to Fig. 1, but showing the parts in the positions assumed just before the compressor is shut off by the main control, the feeler being at the rearward end of its normal operating path;

Fig. 3 is a view similar to Fig. 1, but showing the parts in the positions assumed just after the main control has started the compressor, the feeler being at the forward end of its normal 50 operating path;

Fig. 4 is a view similar to Fig. 1, but showing the parts in the positions assumed after the auxiliary control has been operated, due to the stopping of the feeler during its forward normal operating stroke, to prevent starting of the compressor;

Fig. 5 is a view corresponding to Fig. 1, but illustrating control of the intermittent action of the compressor and control of the defrosting device in accordance with changes in temperature in the space cooled by the refrigerating system;

Fig. 6 is a diagrammatic view illustrating one embodiment of the present invention applied to a refrigerating system of the absorption type, both 60 the intermittent action of the refrigerating system and the action of the defrosting means being controlled in accordance with changes in temperature in the space to be cooled; and

Fig. 7 is a sectional view illustrating one form 70 of valve for control by the defrosting device for shutting off the supply of gas to the burner of the absorption system.

Referring to Fig. 1, 10 designates a compressor from which a suitable refrigerant, such, for 75 example, as sulphur dioxide, is forced past the

check valve 11 to a condenser 12 in which the refrigerant heated during compression is cooled. From the condenser the refrigerant passes to a receiver or reserve reservoir 13 connected in a suitable manner, as by conduit 14, with a cooling element or unit 15. Admission of the liquid refrigerant to the cooling unit or evaporator 15 may be controlled by suitable means such as an expansion valve (not shown) and a float operated valve (not shown). From the cooling element 10 or evaporator 15 the expanded refrigerant is returned through a suitable conduit or pipe 16 to the compressor into which it is drawn past a check valve 17 designed to prevent return of the refrigerant into the suction line 16. 15

Preferably, the compressor is driven by an electric motor 18 which may be coupled directly to the compressor or indirectly as by means of reduction gearing (not shown). As here disclosed, the rotor of the motor is directly connected with a shaft 19 carrying a crank 20 which is connected with the piston of the compressor by means of a connecting rod 21. Power for actuating the motor 18 is provided through a circuit 22 and intermittent action of the motor 25 may be obtained during ordinary operation by means of a control 23 having a connection 24 with the receiver 13 and adapted to open the circuit 22 when the pressure in the receiver 13 equals or exceeds a predetermined value and to 30 close the circuit 22 when the pressure in the receiver 13 drops to or below a predetermined pressure. Preferably, the circuit 22 is also provided with a hand switch 24a.

When the ice accumulates on the cooling element 15 up to a predetermined thickness, it becomes necessary to defrost or remove ice from the cooling element. Heretofore, defrosting has been effected by manually shutting off the compressor and maintaining it in that condition until the ice has melted to a predetermined thinness. The present invention contemplates automatic defrosting of the cooling element, as by means for opening and closing the circuit 22 independently of the action of the control device 23. Such 45 opening and closing of the circuit may be effected by a switch 25 including a fixed contact 26 and a movable contact 27 controlled by the automatic defrosting means, which may include a motor or actuating portion operated in accordance with 50 changes in pressure in the receiver 13, a feeler 28 movable toward and from the cooling element 15, a device for controlling the switch 25, and means 55 interposed between the motor element on the one hand and the feeler 28 and the switch operating device on the other hand, whereby the motor element normally acts to reciprocate the feeler but upon engagement of the feeler with ice of excessive thickness on the cooling element acts to open the switch 27.

Preferably such interposed means includes a closed system filled with substantially incompressible fluid, preferably a liquid having a boiling point above the maximum and a freezing point below the minimum temperature to which the device will be subjected in operation, and is provided with a Sylphon 29 for operating the feeler 28, a Sylphon 30 for controlling the switch 25, and an actuating Sylphon 31 controlled by the motor element. Obviously, contraction of the Sylphon 31 will cause expansion of one or both of the Sylphons 29 and 30, and expansion of the Sylphon 31 will cause contraction of one or both of the Sylphons 29 and 30. It will be understood that one end of each of the Sylphons 29, 30 and 75

31 is normally held in fixed position and that the other end is in each case left free for movement with respect to the fixed end. The feeler 28 is connected with the free end of the Sylphon 29 and preferably consists of a plate or disc 32 to engage the ice and a rod 33 extending axially with respect to the disc 32 to the free end of said Sylphon 29 to which it is secured so as to extend perpendicularly therefrom. Preferably the plate 32 and also the rod 33 are composed of material having a low thermal conductivity, for example, hard rubber or fibre.

10 The Sylphon 29 may be supported at its inner end on a bracket 34 adjustably mounted on a fixed support 35 by means of a bolt or screw projecting through a slot 37 in the base of the bracket. This enables the Sylphon 29 to be adjusted toward and from the cooling element 15 to adjust the position of the feeler with relation thereto. The inner end of the Sylphon 30 may be mounted on a bracket 38 fixedly secured on a support 39, the outer end of the Sylphon 30 having fixed thereto the movable member 27 of the switch 25 which is normally kept closed by 25 yielding pressure exerted on the outer head or end of the Sylphon 30, as by means of a spring 40 of suitable strength interposed between the outer end of said Sylphon 30 and a fixed member such as a bracket 41 secured in fixed position 30 on the support 39. The inner end of the Sylphon 31 may also be supported by a fixed bracket 42 preferably fixed on a fixed support 43.

35 The closed system containing the Sylphons 29, 30 and 31 may also include a pressure conduit or pipe 44 connecting Sylphons 29 and 31 and a conduit 45 connecting conduit 44 with Sylphon 30. It will be evident there must be some flexibility between Sylphons 29 and 31 to enable adjustment of bracket 34 while bracket 42 remains 40 stationary. This flexibility may be obtained in various ways—for example, by providing conduit 44 with an expansion coil or loop 46 which also prevents interference with pipe or conduit 45.

45 In carrying out the present invention, the arrangement should be such that the feeler 28 would be advanced as the system approaches a condition for again starting the compressor and retracted as a result of such restarting, and that upon contact of the feeler during its forward 50 movement with ice of excessive thickness the auxiliary control or switch 25 would be operated just before the system reaches the condition to cause action by the control 23 to start up the compressor. If the defrosting is to be 55 controlled by pressure conditions, the feeler 32 should be advanced as the pressure decreases in the pressure or high side of the system. This may be done by connecting the pressure line 24 by a branch 47 with the adjacent end of a Sylphon 48, which end is carried on a bracket 49 fixedly mounted on the fixed support 50. For connection with the Sylphon 31, the other end of this Sylphon may be provided with a rod 51 guided in a bracket 52 secured to a fixed support 53 and pivotally connected with one end of a lever 54 centrally pivoted at 55 and pivotally connected at its other end with a rod 56 attached to the free and outer end of the Sylphon 31.

60 70 It will be evident that, with this arrangement, a drop in pressure in the receiver 13 and connection 24 will tend to contract the Sylphon 48 and through the lever 54 compress the Sylphon 31. This would ordinarily expand the Sylphon 29 and advance the feeler 28 toward the cooling

65 element 15. If the ice on the cooling element had not reached the predetermined thickness the feeler would merely advance to the forward end of that movement determined by the low pressure at which the main control acts to start 5 the compressor 10.

70 When the feeler is thus advanced to the end of its normal movement without striking the ice on the cooling element there is no need for defrosting and the switch 25 remains closed. 10 The pressure in the receiver and its connection to the control 23 falls until this control is operated to start the compressor 10, the action of which continues until the pressure in the receiver 13 reaches the predetermined degree 15 whereupon the control 23 is again operated to stop the motor 18. During this building up of pressure the feeler 28 has been retracted to its rearward position determined by a spring 62 interposed between the bracket 52 and the free 20 end of the Sylphon 48. This spring may be of such strength and characteristics as to provide for a range of movement of the Sylphon 48 requisite for the proper operation thereof under variations of pressure to which it is subjected in 25 operation.

30 This spring 62 also assists in contracting or collapsing the Sylphon 48 when the pressure in the receiver falls and helps to overcome the spring 40 and the resistance of the Sylphon 30 30 and open the switch 25 when the feeler 28 engages ice of the predetermined maximum thickness on the cooling element 15.

35 The operation of the apparatus is substantially as follows: During operation of the compressor, pressure is built up in the receiver 13 until it reaches the predetermined maximum at which the main control 23 acts to open the circuit 22 and stop the motor 18 and the compressor 10. Then the pressure in the receiver 13 40 gradually drops as the liquid passes therefrom to the cooling unit 15 until the pressure reaches the predetermined point at which the main control 23 is set to restart the motor and the compressor. The Sylphon 48, is, of course, subjected to the same internal pressure as the receiver 13 and expands against the action of the spring 62 as the pressure increases and contracts when the pressure falls. This Sylphon 48 is so constructed and designed and the spring 62 is of 45 such strength or so adjusted that the Sylphon will be at its maximum desired expansion when subjected to the maximum pressure in the receiver. Due to the connection between Sylphon 48 and Sylphon 31, the latter will be at its maximum desired expansion at the same time as Sylphon 48 and at the same time the Sylphons 29 and 30 will be in their condition of maximum contraction, causing the feeler 28 to be at its maximum distance from the cooling element 15, 50 and movable contact 27 will be in engagement with fixed contact 26 at the switch 25. (See Fig. 2.)

55 Following the stopping of the motor 18 by the main control 23, the pressure in the receiver falls, 60 causing contraction of the Sylphons 48 and 31 and tending to expand the Sylphons 29 and 30. Expansion of the Sylphon 30, however, is resisted by the spring 40 so that the only expansion is that 65 of Sylphon 29 and the feeler 28 is advanced toward the cooling element 15. Thus, if advance of the feeler 28 is not opposed during the contraction of Sylphon 48 caused by the drop in pressure to the point at which the main control 23 restarts the compressor, contacts 26 and 27 70 75

will remain in engagement with each other and the control 23 will restart the motor and the compressor in the usual manner, thus serving to retract the feeler 28 from the forward end of its 5 normal operating path. This intermittent operation of the compressor will continue until the ice 63 on the cooling unit reaches the predetermined maximum thickness (Fig. 4) to operate the defrosting means.

10 The Sylphon 29 is so positioned by adjustment of the bracket 34 that, when the pressure in the receiver 13 has fallen to the point where the main system control 23 would normally start the compressor, the corresponding condition of expansion of the Sylphon 29 would cause positioning of the disc 32 of the feeler 28 at such a distance from the cooling element 15 as to cause the disc to strike the ice coating 62, if the ice be of the maximum thickness desired, somewhat before the condition for starting the compressor is reached. Then since further movement of the feeler and expansion of the Sylphon 29 are prevented before the normal contraction of Sylphons 48 and 31 is completed, the further contraction of these Sylphons will cause the expansion of Sylphon 30 against the action of spring 40 and opening switch 25, thus preventing starting of the motor by the main control 23.

The fall of pressure in the receiver 13 will continue until the pressure throughout the main refrigerating system is equalized. This fall in pressure will tend to cause further contraction of Sylphons 48 and 31 and further expansion of Sylphon 30 until contraction of Sylphon 48 is checked by engagement of the hooked lug 57 on the free end thereof with the adjustable bracket or stop 58 which is so adjusted that the feeler disc 32 will have advanced to a point short of that corresponding with the minimum thinness (Fig. 4) of the ice coating for defrosting sufficient to permit the Sylphon 30 to contract under the influence of the spring 40 to bring the contact 27 into engagement with the contact 26, thus closing the switch 25 and restoring the motor 18 to the control of the main control 23. It will be seen that during the defrosting operation the disc 32 of the feeler 28 will continue to be pressed against the surface of the ice coating and will advance as such surface recedes, due to the pressure exerted by the spring 40, until the Sylphon 30 reaches its full allowable degree of contraction and causes closing of the switch 25.

It should be noted that the Sylphon 30 with the spring 40 cooperating therewith has three functions: (1) to open and close the switch 25; (2) to supply the pressure to expand the Sylphon 29 and advance the feeler 28 after Sylphons 48 and 31 have reached their maximum degree of contraction; and (3) to limit the maximum possible pressure in the closed system containing the Sylphons 29, 30 and 31. This limitation of pressure is necessary in view of the fact that ice will melt under heavy pressure and excessive pressure of the disc 32 against the coating of ice on the cooling element would cause faster melting of the ice opposite the feeler than at other points thus causing the restarting of the compressor before the cooling element is suitably defrosted.

It should also be noted that the disc 32 of the feeler 28 cannot be frozen to the surface of the ice coating on the cooling element and thus interfere with proper operation, in that the disc does not come into contact with the surface of the ice coating during normal operation and, when it 75 does engage the ice, the defrosting device is

caused to operate to produce defrosting or melting of the coating. Furthermore, as soon as the ice has been melted to the predetermined degree of thinness (Fig. 1) the compressor 18 is started and immediately acts to increase the pressure in the receiver 13 and withdraw the disc from the cooling element 15 before any substantial effect to freeze it fast to the cooler can be produced by the refrigerating or freezing action which is resumed as soon as the compressor starts.

10 During the defrosting operation the water resulting from the melting of the ice coating on the cooling element 15 will drip therefrom. Obviously, it will be necessary to arrange for the disposal of this drainage water as, for example, by 15 the use of a drip pan 64, normally supported under the cooling element and removable for emptying.

While the motor element of the defrosting device which has just been described is actuated by the variation in pressure in that part of the 20 refrigerating system which is on the discharge side of the compressor, commonly known as the "high side" of the system, it will be understood that the motor element may be actuated by the variation in pressure in that part of the refrigerating system which is on the suction side of the compressor, commonly known as the "low side" or "suction side" of the system. It will be understood that in such case the device is so arranged that an increase of pressure in the "low side" of 30 the refrigerating system will move feeler toward the cooling unit and a decrease in pressure in the refrigerating system will withdraw feeler from cooling unit. In other words, Sylphon 48 will be so connected to Sylphon 31 as to cause contraction of Sylphon 31 when Sylphon 48 expands and to cause expansion of Sylphon 31 when Sylphon 48 contracts, and stop 58 and hook 57 will be so arranged as to limit or stop the expansion of Sylphon 48 at any desired point.

40 The motor element of the defrosting device or control may be of a thermostatic type and preferably devices of this type are used in connection with refrigerating systems in which the main control is thermostatic. In Fig. 5 there is shown an illustrative embodiment of a defrosting device 45 thermostatically controlled and applied to a system similar in general to that shown in Fig. 1 but having a main control 23a of the thermostatic type effective to open the motor circuit when the temperature in the compartment to be cooled or of the cooling unit itself drops to a predetermined minimum and to close the motor circuit when the temperature rises to a predetermined maximum. The only feature by which the defrosting device of Fig. 5 differs substantially from that of Fig. 1 resides in the inclusion of a thermostatic device in the means for controlling the Sylphon 31 and the omission of any control by variations of pressure in the receiver.

55 The thermostatic device disclosed for purposes of illustration is in the form of a bimetallic strip 65 secured at one end to a fixed member 66 and pivotally connected at its other end with a connecting rod or link 67 which is pivotally connected with a member or rod 56a secured to the free end of the Sylphon 31 and positioned substantially axially with respect thereto. In order to limit the contraction of the Sylphon 31 and the advance of the feeler 28, the rod 56a may be 60 provided with a transversely projecting lug 57a adapted to limit the contraction of the Sylphon 31 by engagement with an adjustable bracket or stop 58a secured on the fixed member 43 by means of a bolt or screw 68 passing through a slot 69 65

in the base of the bracket. In order to avoid excessive stresses and possible breakage when the bimetallic strip 65 tends to advance the rod further than the position determined by the adjustable stop 58a, suitable provision for yielding is made in the train of connections, as by connecting the adjacent end of the connecting rod 67 with the rod 56a by pivotally connecting the former with a block 70 mounted to slide in a slot 10 in the end of the rod and normally held at the outer end of the slot by means of a helical spring 72 interposed between the block and the other end of the slot. The operation is substantially the same as described in connection with the apparatus shown in Fig. 1.

In Fig. 6, there is illustrated an application of a thermostatically controlled defrosting device to an absorption system. The defrosting device may be of any suitable form but for convenience is illustrated as being the same as that disclosed in Fig. 5 except that it is utilized to control the supply of gas to a burner of an absorption system which may be of any suitable form but for convenience is illustrated as being of Munsters-25 Platen type shown and described on pages 252 to 258, inclusive of "The Handbook of Refrigerating Engineering" by W. R. Woolrich, published by D. Van Nostrand Company, Inc., New York, N. Y., 1929. The absorption system here shown 30 includes an evaporator 75, an absorber 76 having a water jacket, and a connection 77 between the upper part of the absorber and the upper part of the evaporator. At the time of manufacture of the apparatus, hydrogen at a suitable pressure, 35 150 pounds absolute for example, is sealed in the system and occupies the upper part of the evaporator, the upper part of the absorber and the connecting piping or connection 77. The refrigerant used is ammonia originally in the form of 40 aqua ammonia located between the inner and outer walls of an annular tubular generator 78 which may be heated by a gas burner 79 at the bottom thereof.

When the aqua ammonia is boiled in the generator, ammonia gas is given off and the original 45 150 pounds of hydrogen pressure is increased by say 20 pounds absolute, thus making the total pressure 170 pounds absolute. In this boiling there are formed ammonia gas bubbles which 50 carry globules of rich liquor up the thermo-Syphon tube 78a to the top of the generator. The ammonia gas from the generator is passed through a rectifier (not shown) where some cooling takes place, the liquid aqua ammonia 55 separating out and draining back to the generator and the dry ammonia gas passing through a condenser 80 which may be of the double tube type with cooling water passing between the two tubes. The ammonia thus condensed flows from 60 the condenser into the evaporator 75 where it vaporizes just fast enough to nearly balance the pressures in the generator and the evaporator, in that too rapid evaporation will raise the pressure in the evaporator 75 and prevent the flow of 65 ammonia to the same.

As the condensed ammonia evaporates in said evaporator, it diffuses with the hydrogen there present and the diffused gas being heavier than hydrogen will fall to the bottom of the evaporator 70 and pass therefrom through a pipe 81 to the bottom of the absorber 76 which is at a lower level. The ammonia here combines with weak liquor entering the absorber thus releasing hydrogen which goes to the top of the absorber 75 and forming strong liquor which passes back to

the generator through a pipe 82 which forms the inner tube of a double tube 83 through the outer part of which passes in the opposite direction weak liquor received from a pipe 84 connected with a higher point of the generator and discharged through a pipe 85 extending upwardly in the water jacket of the absorber to the upper part of the absorber proper. The cooling water is supplied through a pipe 86 which communicates with the lower part of the water jacket of the absorber and passes from this water jacket to the outer tube of the condenser 80 from which it is discharged through a pipe 87.

The flow of gas to the burner 79 may be shut off automatically by a main thermal control 88 associated with the gas supply line 87, when the temperature drops too low, and turned on automatically when the temperature rises to a predetermined degree, the relighting of the burner being effected by means of a pilot light 88. The defrosting device is just the same as that shown in Fig. 2 except that the Syphon 30 acts through a member 27a secured to the free end thereof to close a quick-acting valve 89 when the ice on the cooling element or evaporator 75 reaches a predetermined thickness, and to open the valve when the ice is melted to a predetermined thinness.

As shown in Fig. 7, the valve 89 may take the form of a flat casing to which sections of the pipe or line 87 are connected at the opposite flat faces and the opening or closing of the valve may be effected by means of a member 90 inside the casing at the discharge side thereof and provided with an opening 91 which registers with the outlet opening of the casing when the member or slide is held in its raised position by a member or link 92 passing through the upper part of the casing and pivotally connected with the member 27a. When the Syphon 30 is expanded due to engagement of the feeler with ice of a maximum thickness on the cooling element or evaporator 75, the slide 90 will be lowered sufficiently to close the outlet of the casing of the valve 89. The slide 90 may be kept in close engagement 45 with the outlet face of the casing by suitable means such as a bow spring 93 having one end fastened to the opposite side of the casing and the other end free but resting against the same side of the casing. It should be understood that 50 the spring 93 does not cover the opening 91 in the slide 90 when the latter is in its Fig. 7 position but is at one side of the opening.

It may be desirable to maintain the normal operation of the refrigerating system under conditions which would otherwise result in defrosting. Such maintaining of the normal operation may be obtained by suitable means such as a manually operated switch 94 in shunt or parallel with the switch 25 in the electric refrigerating 55 systems shown in Figs. 1 to 5, inclusive. This switch would, of course, be open under ordinary circumstances but would be closed when it was desired to assure continuance of the usual refrigerating action without defrosting. It will be 60 evident that switch 24a provides for throwing the whole system out of operation or for starting it.

In the absorption system shown in Fig. 6 maintenance of normal operation may be assured, 70 regardless of conditions which would ordinarily cause defrosting by providing a by-pass around the defrosting-control valve 89 and a valve 95 to control the by-pass. When valve 95 is open, the defrosting unit cannot produce defrosting. 75

This system may also be provided with a valve 96 in the fuel line 87 adapted, when closed, to shut down the entire system.

It should be understood that the present invention is applicable to refrigerating systems of other types than those disclosed and that, although it is desirable to use a pressure-operated motor element for a defrosting device used with a refrigerating system controlled in accordance with pressure therein and to use a thermostatic motor element when the main control is thermostatic, it is not necessary to do so.

The foregoing detailed description has been given for clearness of understanding and no undue limitation should be deduced therefrom, but the appended claims should be construed as broadly as possible in view of the prior art.

Having thus described my invention, I claim:

1. The combination with a refrigerating system including a cooling element, means for supplying refrigerant to said cooling element in condition to cool the same and controlling means for starting and stopping the operation of the refrigerant-supplying means in accordance with changes of condition in connection with said system, of defrosting means including an auxiliary control for preventing or permitting operation of the refrigerant-supplying means, a closed system containing a suitable fluid and having at one point a movable part adapted to exert pressure in the closed system, a second movable part movable toward or from the cooling element in accordance with increase or decrease of pressure exerted by movement of the first movable part and a third movable part movable outwardly and inwardly in accordance with increase or decrease of pressure exerted by movement of the first movable part, a feeler connected with the second movable member, a connection between the third movable part and the auxiliary control, and yielding means tending to prevent movement of the third movable part but movable upon engagement of the feeler with ice of excessive thickness on the cooling element to prevent operation of the refrigerant-supplying means, and acting upon melting of the ice to a predetermined thinness to restore the refrigerant-supplying means to the control of said controlling means.

2. The combination with a refrigerating system including a cooling element, means for supplying refrigerant to said cooling system in condition to cool the same and controlling means for starting and stopping the operation of the refrigerant-supplying means in accordance with changes of condition in connection with said system, of defrosting means including an auxiliary control for preventing or permitting operation of the refrigerant-supplying means, a closed system filled with a suitable liquid and including three interconnected Sylphons with their inner ends held in fixed positions, a feeler connected with the outer end of one of said Sylphons for movement thereby toward and from the cooling element, means connected with the outer end of one of the other Sylphons for moving such end inwardly when a condition requiring fresh refrigerant in the cooling element is approached and outwardly after such fresh refrigerant has been supplied, a connection between the outer end of the third Sylphon and the auxiliary control to operate the same to prevent action of the refrigerant-supplying means when said third Sylphon is expanded, and yielding means normally preventing expansion of the third Sylphon but adapted to be overcome when the feeler

comes into engagement with a layer of ice of predetermined thickness on the cooling element and permit operation of the auxiliary control but to return the parts to normal position upon melting of the ice to a predetermined thinness and the resulting forward movement of the feeler.

3. The combination with a refrigerating system including a compressor, a condenser, and a cooling element to which the condensed refrigerant is supplied, compressor-actuating means and a pressure-operated main control for said compressor-actuating means connected by a pressure line with the refrigerating system of an auxiliary control for preventing or permitting operation of the compressor-actuating means, a feeler movable toward and from said cooling element, a closed system containing a suitable liquid and including three Sylphons fixed at their connected inner ends and having their outer ends movable to permit expansion or contraction, said Sylphons including one connected with the auxiliary control to operate the same, a second one connected with the feeler to operate the same and a third or actuating Sylphon operated to expand and contract the others, pressure means connected with said pressure line for contracting and expanding said actuating Sylphon in accordance with changes of pressure in said pressure line, and yielding means normally preventing expansion of the auxiliary-control-operating Sylphon.

4. The combination with a refrigerating system including a compressor, a condenser, and a cooling element to which the condensed refrigerant is supplied, compressor-actuating means and a pressure-operated main control for said compressor-actuating means connected by a pressure line with the refrigerating system, of an auxiliary control for preventing or permitting operation of the compressor-actuating means, a feeler movable toward and from said cooling element, a closed system containing a suitable liquid and including three interconnected Sylphons fixed at their connected inner ends and having their outer ends movable to permit expansion or contraction, said Sylphons including one connected with the auxiliary control to operate the same, a second one connected with the feeler to operate the same and a third or actuating Sylphon operated to expand and contract the others, yielding means normally preventing expansion of the auxiliary-control-operating Sylphon, and means for expanding and contracting said actuating Sylphon in accordance with change of pressure in said pressure line including a fourth Sylphon connected at its inner fixed end with said pressure line and connections between the outer end of the fourth Sylphon and the outer end of the actuating Sylphon whereby they act in unison.

5. The combination with a refrigerating system including a compressor, a condenser, and a cooling element to which the condensed refrigerant is supplied, compressor-actuating means and a pressure-operated main control for said compressor-actuating means connected by a pressure line with the refrigerating system between the condenser and the cooling element, of an auxiliary control for preventing or permitting operation of the compressor-actuating means, a feeler movable toward and from said cooling element, a closed system containing a suitable liquid and including three interconnected Sylphons fixed at their connected inner ends and having their outer ends movable to permit expansion or contraction, said Sylphons including one connected with the auxiliary control to operate the

same, a second one connected with the feeler to operate the same and a third or actuating Sylphon operated to expand and contract the others, yielding means normally preventing expansion of the auxiliary-control-operating Sylphon, means for operating said actuating Sylphon in accordance with rise or fall of pressure in said pressure line including a fourth Sylphon connected at its inner fixed end with said pressure line, connections between the outer end of the fourth Sylphon and the outer end of the actuating Sylphon whereby they act in unison, and yielding means resisting the expansion of the fourth Sylphon, thereby tending to limit the rearward movement of the feeler and to assist in advancing the feeler and operating the auxiliary control.

6. The combination with a refrigerating system including a compressor, a condenser, and a cooling element to which the condensed refrigerant is supplied, compressor-actuating means and a pressure-operated main control for said compressor-actuating means connected by a pressure line with the refrigerating system, of an auxiliary control for preventing or permitting operation of the compressor-actuating means, a feeler movable toward and from said cooling element, a closed system containing a suitable liquid and including three interconnected Sylphons fixed at their connected inner ends and having their outer ends movable to permit expansion or contraction, said Sylphons including one connected with the auxiliary control to operate the same, a second one connected with the feeler to operate the same and a third or actuating Sylphon operated to expand and contract the others, yielding means normally preventing expansion of the auxiliary-control-operating Sylphon, means for varying the capacity of said actuating Sylphon with rise and fall of pressure in said pressure line including a fourth Sylphon connected at its inner fixed end with said pressure line, yielding means resisting the expansion of said fourth Sylphon, connections between the outer end of said fourth Sylphon and the outer end of said actuating Sylphon to cause them to act in unison, and means for limiting the movement of said fourth Sylphon to limit contraction of the third Sylphon.

7. The combination with a refrigerating system including a compressor, a condenser, and a cooling element to which the condensed refrigerant is supplied, compressor-actuating means and a thermostatic main control for said compressor-actuating means, of an auxiliary control for preventing or permitting operation of the compressor-actuating means, a feeler movable toward and from said cooling element, a closed system containing a suitable liquid and including three interconnected Sylphons fixed at their connected inner ends and having their outer ends movable to permit expansion or contraction, said Sylphons including one connected with the auxiliary control to operate the same, a second one connected with the feeler to operate the same and a third or actuating Sylphon operated to expand and contract the others, yielding means normally preventing expansion of the auxiliary-control-operating Sylphon, means for expanding and contracting said actuating Sylphon including a thermostatic device, and a connection between said thermostatic device and the outer end of the actuating Sylphon, and means for limiting the contraction of the actuating Sylphon.

8. The combination with a refrigerating system including a compressor, a condenser, and a cooling element to which the condensed refrigerant is

supplied, compressor-actuating means and a thermostatic main control for said compressor-actuating means, of an auxiliary control for preventing or permitting operation of the compressor-actuating means, a feeler movable toward and from said cooling element, a closed system containing a suitable liquid and including three interconnected Sylphons fixed at their connected inner ends and having their outer ends movable to permit expansion or contraction, said Sylphons including one connected with the feeler to operate the same and a third or actuating Sylphon operated to expand and contract the others, yielding means normally preventing expansion of the auxiliary-control-operating Sylphon, means for expanding and contracting said actuating Sylphon including a thermostatic device and a connection between said thermostatic device and the outer end of the actuating Sylphon, said connection being strong enough to expand and collapse said actuating Sylphon but yieldable to prevent damage when contraction of such Sylphon is blocked, and a stop device to check the collapse of the actuating Sylphon, thereby causing said connection to yield.

9. The combination with a refrigerating system of the absorption type including a cooling element, a generator, a burner, a fuel supply line for said burner, a main control of the thermostatic type for opening and shutting the supply line in accordance with the demands of the system, and a pilot connected with said supply line at the entrance side of the main control, of an auxiliary control in said supply line for closing and opening the supply line thereby preventing or permitting heating of said generator, a feeler movable toward and from said cooling element, a closed system containing a suitable liquid and including three interconnected Sylphons fixed at their connected inner ends and having movable outer ends to permit expansion or contraction, one of said Sylphons being connected with the auxiliary control, a second one being connected with the feeler to operate the same, the third or actuating Sylphon being operated to expand or contract the others, yielding means normally preventing expansion of the auxiliary-control-operating Sylphon, means for expanding and contracting said actuating Sylphon including a thermostatic device and a connection between said thermostatic device and the outer end of the actuating Sylphon, said connection serving to actuate the feeler or the auxiliary control when the feeler is blocked and yielding when contraction of the actuating Sylphon is prevented, and a stop device to limit the collapse of the actuating Sylphon.

10. The combination with a refrigerating system including a compressor, an electric motor for operating said compressor, a circuit to supply power to said motor, a condenser, a cooling element, and a pressure-operated main control connected with the interior of the refrigerating system and adapted to open said circuit and close said circuit when the pressure reaches predetermined limits, of an auxiliary control for the compressor-actuating means including a second-switch in said circuit, a feeler, means controlled by the pressure in said system during normal operation for moving the feeler toward said cooling element while the compressor is idle and from said cooling element when the compressor is working, and for opening and closing said second-switch at other times, yielding means tending to hold said switch closed, and a manually controlled switch in parallel with said second-switch.

11. The combination with a refrigerating system including a compressor, an electric motor for operating said compressor, a circuit to supply power to said motor, a condenser, a cooling element, and a thermostatic main control adapted to open said circuit and close said circuit when the temperature reaches predetermined limits, of an auxiliary control for the compressor-actuating means including a second-switch in said circuit, a 5 feeler, thermostatic means for moving, during normal operation of the refrigerating system, the feeler toward said cooling element while the compressor is idle and from said cooling element when the compressor is working, and for opening and 10 closing said second-switch at other times, yielding means tending to hold said switch closed, and a manually controlled switch in parallel with said 15 second-switch.
12. The combination with a refrigerating system of the absorption type including a cooling element, a condenser from which refrigerant is supplied to said cooling element, a generator, a burner, a fuel supply line for said burner, a thermostatic main control for opening and closing the 20 supply line in accordance with the demands of the system, and a pilot light connected with said supply line at the entrance side of the main control, of an auxiliary control in said supply line, a feeler, means for moving the feeler towards said 25 cooling element when the temperature thereof is falling and from the cooling element when the temperature is rising or for opening and closing said auxiliary control, yielding means normally holding the auxiliary control against closing but 30 permitting it to close when the feeler is stopped by 35 ice on the cooler before it reaches the end of its
- normal operating stroke, and manually controlled means for supplying fuel past said auxiliary control. 5
13. In defrosting apparatus for a refrigerating system embodying a cooling element, the combination of a pressure motor device, a feeler operatively associated therewith and having a predetermined normal range of movement, a refrigeration control device and means, operable upon checking of the feeler short of its normal range of movement, to actuate said control device. 10
14. In defrosting apparatus for a refrigerating system embodying a cooling element, the combination of a thermostatic motor device, a feeler operatively associated therewith and having a predetermined normal range of movement, a refrigeration control device and means, operable upon checking of the feeler short of its normal range of movement, to actuate said control device. 15
15. In defrosting apparatus for refrigerating systems, the combination of a reciprocating feeler, an electric circuit control device, a closed system containing a suitable liquid and including three interconnected Sylphons normally fixed at their connected ends and having their opposite ends 20 movable to permit expansion or contraction, said Sylphons including one connected with the control device to operate the same, a second one connected with the feeler to operate the same, and a third or motor Sylphon operated to expand and 25 contract the others, and yielding means normally preventing expansion of the control-device-operating Sylphon but permitting such expansion upon interference with the movement of the feeler due to the accumulation of ice. 30 35
